Primary Examiner — Wendy L Arminio(74) *Attorney, Agent, or Firm* — WPAT Law, P.C.;
 Anthony King(57) **CLAIM**

The ornamental design for a hygiene rinse cap, as shown and described.

DESCRIPTION

FIG. 1 is a perspective view of the hygiene rinse cap; FIG. 2 is a right side view of the hygiene rinse cap of FIG. 1;

FIG. 3 is a left side view of the hygiene rinse cap of FIG. 1; FIG. 4 is a front view of the hygiene rinse cap of FIG. 1; FIG. 5 is a back view of the hygiene rinse cap of FIG. 1; FIG. 6 is a top view of the hygiene rinse cap of FIG. 1; and, FIG. 7 is a bottom view of the hygiene rinse cap of FIG. 1. The broken lines depict portions of the hygiene rinse cap that form no part of the claimed design.

1 Claim, 5 Drawing Sheets(56)
